UNITED STATES PATENT OFFICE

WALTER F. TROTTER, OF CHARLESTON, WEST VIRGINIA, ASSIGNEE, BY MESSRS. A. H. G. M. M., TO THE JEFFREY MANUFACTURING COMPANY, A CORPORATION OF ILLINOIS.

MINING-MACHINE.

1,127,701.

Specification of Letters Patent.

Patented Feb. 16, 1915.

Application filed September 20, 1907, Serial No. 393,831. Renewed January 28, 1913. Serial No. 412,779.

To all whom it may concern:

Be it known that I, WALTER F. TROTTER, a citizen of the United States, residing at Charleston, in the county of Kanawha and State of West Virginia, have invented certain new and useful Improvements in Mining-Machines, of which the following is a specification, reference being had therein to the accompanying drawing.

10 This invention relates to improvements in mining machines, particularly to side cutting mining machines. It has been proposed heretofore to provide machines of this class with flexible draft devices adapted to propel the machine along the face of the coal and to guide it or hold it to its work. In some cases cables were to be used as the flexible draft and holding members, and in other cases the functions of propelling and guiding the machine were to be performed by chains in connection with sprocket mechanisms or the like on the machines adapted to engage positively and rigidly with the chains. In one form of these latter machines, for example, a single continuous chain is provided having one end fixed to an anchor or the like in advance of the machine and its other end fixed to an anchoring device on the rear side of the machine, 20 while intermediate its ends the chain passes over sprocket drive mechanisms on the machine.

25 My invention, in the preferred form, contemplates the use of cables for propelling and guiding the machine and is intended to provide a machine in which are overcome certain disadvantages and difficulties that have heretofore been experienced in the propelling and guiding of side cutting machines, especially in room and pillar mining.

30 The nature and all of the various objects of the invention will be understood in detail from the following description in connection with the drawings.

35 Figure 1 is a plan view of a mining machine embodying my improvements. Fig. 2 is a section on the line 2—2, Fig. 1. Fig. 3 is a side elevation of the same. Figs. 4 and 4a are enlarged sections on the line 4—4, Fig. 1, showing the operative mechanism and the cutter frame, respectively. Fig. 5 is an enlarged section on the line 5—5, Fig. 1. Fig. 6 is an enlarged section on the line 6—6, Fig. 1. Fig. 7 is a plan view of the 40 inner portion of the cutter carrier and the

guiding mechanism, for feeding it transversely to the coal face. Fig. 8 is a section on the line 8—8, Fig. 7, the adjustable jack being removed. Fig. 9 is a view partly in elevation and partly in section of the jack stand and jack. Fig. 10 is a reduced plan view showing the mining machine arranged to feed transversely to the coal face at the beginning of a cut. Fig. 11 is a reduced plan view showing the mining machine and its operating parts arranged to feed laterally along the coal face. Fig. 12 is an enlarged side elevation partly in section of the guide-cable winding drum. Fig. 13 is an enlarged side elevation of the ratchet lever 70 used in connection with the guide-cable drum.

For the purpose of illustration I have shown in the drawing a mining machine of which A indicates the main frame as an entirety, B the cutting apparatus extending from the inner end thereof and supported thereby, C the feeding and guiding mechanism for advancing the cutting apparatus and machine either longitudinally or laterally, D the motor mechanism, and E the auxiliary parts employed when it is desired to have the cutting apparatus advanced into the coal transversely to the face thereof.

The main frame may be of any suitable construction as far as some features of my invention are concerned, but for reasons which will later appear, I prefer a construction of the character shown. This construction comprises a shoe 1 adapted to rest upon the ground with freedom to slide freely in all directions, longitudinally arranged angle bars or plates 2, 2 secured to said shoe at either side thereof and a suitable platform 3 resting upon and secured to said longitudinal side bars.

4, 4 are webs or plates depending from the platform 3 and carrying at their lower ends the laterally turned longitudinally extending cutting apparatus guides 5, 5.

100 The main frame thus constructed constitutes a box which is closed on all sides except the inner and outer ends. It will be observed on reference to Figs. 3 and 4 that the platform 3 extends at its outer end beyond the bottom plate or shoe 1 and that the side plates 2 are correspondingly cut away. In other words, the outer end of the upper platform part of the main frame overhangs considerably.

- The cutting apparatus comprises a longitudinally arranged horizontally disposed base plate 6, two longitudinally arranged horizontally disposed guide plates, 7, above said base plate and spaced therefrom by the longitudinally arranged bars 8 so as to form a chain guide or recess 9, the parts just referred to being secured together in any suitable manner, as by rivets 10.
- 10 11 is an inner sprocket wheel mounted upon a vertical axle 11', and between the inner end of the base plate 6 and a top plate 12 suitably secured to the base plate and having an outwardly extending centrally arranged part 12' fitted snugly between the top bars 7, 7 of the chain frame.
- The motor D is suitably secured upon the platform 3 with its armature shaft 13 arranged longitudinally of the machine.
- 20 14 is a longitudinally arranged shaft, preferably having its axis in the vertical longitudinal plane of the axis of the chain frame. It is suitably mounted at either end in bearings 14', 14'', one of which is carried by a bearing standard 14^a suitably secured to the platform 3. The inner standard 14^a extends transversely of the machine in either direction from the shaft 14 for the purpose to be hereinafter described.
- 30 15 is a spur gear rigidly secured to the shaft 14 and meshing with a pinion 16 secured to the inner end of the armature shaft 13.
- 17 is a bevel pinion loosely mounted on the shaft 14 near the outer end thereof. 18 indicates a positive clutch interposed between the said shaft 14 and the bevel pinion 17, the longitudinally stationary element 18' of said clutch being secured to the said bevel pinion and the longitudinally movable element 18^a being applied to the shaft.
- 18^b indicates suitable mechanism for moving the element 18^a of the clutch in either direction.
- 40 19 is a vertically disposed shaft suitably mounted in bearings carried by the main frame of the machine and having its axis in the vertical plane containing the axis of the shaft 14. 20 is a bevel gear secured to the upper end of the said vertical shaft and in mesh with the bevel pinion 17.
- 21 is a sprocket drive wheel rigidly secured to the lower end of the vertical shaft 19.
- 22 indicates as an entirety an endless cutter chain or carrier extending around the sprocket drive wheel 21 and the inner sprocket 11 carried by the cutter frame, it being arranged at either side within the guides 9 of the said cutter frame and carrying laterally extending cutters 23 of any suitable construction. The cutter frame is supported from the main frame by the longitudinally arranged slides or guides 5 depending from the main frame and arranged to fit snugly between the base plate
- and the upper plate of the chain frame. The main frame and the chain frame are normally held from longitudinal movement relative to each other by mechanism indicated as an entirety by 24, which also serves 70 as an adjusting means for moving the frames relative to each other to vary the tension upon the cutter chain. The adjusting mechanism 24 comprises a longitudinally arranged screw-threaded shaft 24' mounted 75 near its inner end in a bearing in a depending plate 25 which is secured to the inner end of the main frame platform 3. Near its outer end it is fitted into a threaded nut 26 which is arranged between uprights or 80 projections 27, 27' carried by the base plate 6. The inner end of this shaft is squared as indicated at 24^b to receive a suitable wrench for turning the shaft in either direction so as to extend the chain frame relative to the 85 main frame or to force it in the opposite direction relatively thereto, as desired.
- 28 is a worm gear rigidly secured to the longitudinally arranged shaft 14 near the inner end thereof and between the bearing standard 14^a and the gear wheel 15 secured to the said shaft. 29 is a shaft arranged beneath the said shaft 14 and transversely of the main frame. It is suitably mounted in a bearing 29' secured to the platform of the 95 said frame. 30 is a worm wheel secured to the inside end of the said transverse shaft 29 and in mesh with the worm 28 on the shaft 14.
- 31 is a worm rigidly secured to the out 100 side end of the shaft 29.
- 32 is a longitudinally arranged shaft mounted near either end of the bearings 32', 32'', carried by bearing standards 14^a and 14^a, the latter being arranged parallel to the 105 former and of substantially the same width and secured to the platform of the main frame. The axis of this shaft 32 is in a vertical longitudinal plane on the opposite side of the vertical longitudinal plane of the axis 110 of the shaft 14 from armature shaft 13.
- 33 is a worm wheel rigidly secured to the outer end of the shaft 32 and in mesh with the worm 31 on the transverse shaft 29.
- 34 is a spur gear loosely mounted upon the 115 shaft 32 adjacent to the bearing standard 14^a, and 35 is a gear wheel of greater diameter than the gear wheel 34 and loosely mounted upon the said shaft 32 adjacent to the bearing standard 32'.
- 36 indicates as an entirety clutch mechanism for alternately connecting the gears 34 and 35 to the shaft 32. Of this clutch mechanism 36' indicates a longitudinally movable element splined to the shaft 32 and carrying 120 at one end clutch jaws 36^a adapted to engage clutch jaws 36^b secured to the gear wheel 35 and at its other end clutch jaws 36^c adapted to engage with the clutch jaws 36^d carried by the gear wheel 34.

37 indicates as an entirely suitable mechanism for shifting the movable element 36 of the clutch in either direction at will.

38 is a longitudinally arranged drum shaft 5 suitably mounted near either end in bearings 33', 38^a, in the bearing standards 14^a and 38^a respectively. The axis of this shaft is on the opposite side of the vertical plane containing the axis of the shaft 14 from the 10 axis of the shaft 32.

39 is a gear wheel rigidly secured to the shaft 38 near one end thereof and in mesh with the gear wheel 34 on the shaft 32, and 15 40 is a gear wheel of smaller diameter than the gear wheel 39 and rigidly secured near the opposite end of the shaft 38 and in mesh with the gear wheel 35 on the shaft 32.

41 is a cable winding drum loosely mounted 20 on the shaft 38 and preferably adjacent to the gear wheel 49 at the inner end thereof.

The periphery of the cable drum may be spirally grooved as indicated at 41' to assist in the spooling upon it of a draft cable 44 which has one end suitably fastened to said 25 drum. The drum is preferably connected to the shaft 38 by means of a friction clutch 41^a, one element of which is a ring or casting 41^b carried by the drum and extending outwardly therefrom, and the other element 30 of which is a pulley or ring 41^c having its rim radially slotted at 41^d, 41^e, as indicated. 41^e are adjustable wedges or expanders arranged between the sections of the rim at 35 said slots and adapted to force the periphery of the rim into engagement with the inner walls of the ring 41^c in the well known manner. By varying the adjustment of the expanders the clutch can be made to slip when 40 the resistance to the rotation of the winding drum reaches any given amount.

43 is a pulley or sheave arranged to receive and guide the cable 44 as it is wound upon or is paid out from the drum 41.

42 is a bearing bracket secured to the side plate 2 adjacent to the drum 41. 42' is a longitudinally arranged shaft suitably supported by the laterally extending arm 42^a of the said bracket.

43 is an idler pulley on the shaft 42'. 50 When the machine is in operation and is being advanced along the coal, this pulley guides the draft cable 44 while it is being wound upon the drum.

When the machine is in operation it is advanced along the face of the coal by tension in the draft cable 44 due to the rotation of the drum 41. Under the action of this forward draft, the outer end of the machine tends to swing forward relative to the cutter frame because of the resistance which the coal offers to the advance of the cutters. To 60 overcome this tendency and maintain the machine in proper working position relative to the face of the coal, I use a cable or flexible holder for the outer end of the machine

supplemental to the main draft cable 44. Such cable is indicated at 56. One end is secured to an anchoring device, such as a screw jack 57, on the rear side of the machine and the other end is secured to a winding mechanism on the machine. This preferably comprises a reel or drum 46 to which the end of the cable 56 is secured and which is adapted to permit the unwinding of the cable 56 with the same speed as that at 75 which the cable 44 is wound upon its drum or reel 41. This can be accomplished by connecting the drum or reel 46 to the shafting and gearing which actuate the drum 41. For example, a shaft 48 can be mounted in suitable bearings, as at 48^a, 48^b, along the side of the main frame and to it power can be transmitted from the inner reel gearing, as from the wheel 35. This shaft 48 at the outer end is connected to the drum 46, either directly, 80 in case the desired speeds of the several parts will permit it, or by means of gearing. As shown, it is provided with a gear wheel 47 which meshes with a wheel 49 on the axis of the outer drum or reel. This wheel 49 is 85 keyed to a sleeve 49^a which is rotatably mounted on the cylindrical bearing extension 50^a of the angular bracket 50, said bracket having a horizontal base flange adapted to be bolted to the machine frame. 90 The sleeve has a flange at its outer end formed with ratchet teeth 47'. Between this flange and the gear 49 is arranged the hub of the reel 46. The reel carries a pawl 48' which engages ratchet 47' and is adapted, when in engagement with the ratchet, to prevent rotation of the reel on the sleeve in one direction, the reel being free to rotate in the other direction. A retaining plate 50^b holds the sleeve 49^a in position on the bearing 50^a. A pivot pin 50' is carried by plate 50^b to receive the forked lower end of a pawl lever 51. This lever is adapted to engage the ratchet teeth 46' on the reel to rotate the latter. With devices of this character it will be seen that under ordinary circumstances the two reels 41 and 46 can be in rotation simultaneously to permit the rear cable section to be unwound with the same speed as that incident to the winding of the 105 front cable section. At the same time, as will also be seen, the operator, by means of the hand lever 51, can, if he finds necessary, impart a rotary movement to the drum 46 relative to the sleeve 49^a, thus causing it to 110 revolve more or less independently of the drum 41, and in this way the length and the tension of the rear cable section can be increased or decreased according to the angular adjustment desired for the machine, as 115 an entirely, in relation to its line of travel.

In longwall mining an undercut is usually easily started at a free face, but in room and pillar work an entering or "sumping" cut must be made in order to get the cutting 120

apparatus under the coal, this entering cut being made adjacent one or the other of the ribs constituting the side walls of the room. With my improved machine the sumping 5 cut is made by feeding the machine longitudinally forward so as to project the cutting apparatus into the coal. For this purpose I have devised the combined jack and cutter mechanism guide E illustrated in 10 Figs. 7, 8, 9 and 10. 54 is a base plate of the said jack stand adapted to rest upon the floor of the mine closely adjacent to the coal face and at an angle thereto, as shown. Near either end of this base plate is a pair 15 of upwardly extending arms or lugs 55 supporting between them a shaft or pivot 56^a with its axis arranged longitudinally of the base plate.

57 indicates the jack proper comprising a 20 shank or bar 57^b forked at its lower end as indicated at 57^a, the ends of each arm of said fork being recessed as indicated at 57^b to fit over one of the shafts 56^a on the base plate. The upper end of the jack shank is 25 screw threaded at 57^c to receive a screw threaded hand adjusting wheel 58.

59 is a pointed head for the jack swiveled 30 on the upper end of the jack 57^b and bearing against the upper face of the hub of the wheel 58 by means of which it is adjusted longitudinally of the shank.

54^a is an arm or plate extending laterally from the base plate 54 and carrying the upright bracket 54^a which at its upper end is 35 bifurcated as indicated at 54^b to receive one end of a swinging arm 60, which is pivotally connected to the upright 54^a by means of a bolt 60'. At its free end the arm 60 has pivotally connected to and depending 40 from it a slide 61 which is longitudinally grooved at either side to receive the adjacent longitudinal guide bars 12^b on the chain frame. These guide bars 12^b are rigidly secured in position by means of bolts 45 12^c screw-threaded into inwardly projecting lugs 12^a carried by the base plate 6 of the chain frame. The slide 61 may be introduced into position within the said top plate at the ends of the guides 12^b adjacent the 50 main frame. The slidable connection between the slide 61 and the cutter frame permits the longitudinal movement of the cutter frame relative to the slide while tending to prevent the lateral movement in either 55 direction of the cutter frame relative to the base plate 54. It will thus be seen that when the jack stand is securely fastened in position by means of the jack 57, the cutter frame may be caused to travel forward in a 60 substantially straight line. When the slide 61 reaches the ends of its guides 12^b it may be swung upwardly out of the path of travel of the cutter frame.

To operate the machine for room and 65 pillar work it is unloaded at the corner of

the room where it is desired to begin the cut and with the end of the cutter frame closely adjacent to the face of the coal. The combined jack and cutter frame guide E is then clamped securely in position on the left 70 hand side of the cutter frame near the end thereof, as indicated in Fig. 10, the slide 61 having been introduced into its guide in the top plate of the said frame. The cable 44 is next carried inward from the drum 41 75 along the side of the machine to the inner end of the jack frame and pivotally connected thereto, as indicated at 62, a suitable idler guide 63 serving to direct the course of the cable from the drum toward the said 80 jack stand. This idler guide 63 is mounted on a journal 64 carried by a U-shaped bracket 65 which is pivotally mounted on a longitudinal shaft 66 carried by lugs 67, 67, projecting laterally from the main frame. 85 The U-shaped bracket 65 has a laterally extending lug or projection 65' which is adapted to engage with the platform of the main frame to limit the inward travel of the bracket 65 about the axis of the shaft 66, as 90 indicated in Fig. 6. The bracket 65 may be readily detached by removing the shaft 66, whenever it is not desired to use the idler guide 63.

The motor having been started, the cutting apparatus and the slow-speed gearing of the winding drum are then connected to the motor by clutches 18 and 36 respectively. The drum 41 winds up on the cable and pulls the main frame of the machine toward 95 the coal face, the cutting apparatus simultaneously undercutting the coal. The cutter frame guiding mechanism tends to insure that the cutting apparatus will be moved inward in a substantially straight line. When 100 the slide 61 reaches the ends of the guides 12^b it is withdrawn therefrom and the machine will feed inward without further guiding. The sumping cut having been completed, the machine is stopped, the guide 105 jack E and the idler guide 63 removed, the feed cable 44 extended to the far rib and secured to an anchor or jack 52, and the loose end of the cable 53 secured to an anchor or jack 57 adjacent the rib at which the cut is 110 started. See Fig. 11. The motor is now started and clutches 18 and 36 closed so as to drive the cutters and the winding drum 41 and permit the rotation of the check or retarding drum 46. Ordinarily the winding drum is driven through the slow speed gearing when the cutters are at work, the high speed gearing being used when the propelling cable is employed to move the machine about in the room. The rotation 115 of the winding drum 41 creates tension in the cable 44 tending to advance the machine along the face of the coal. Under the action of the draft of the cable 44 and the resistance which the coal offers to the cutters, 120

the outer end of the machine tends to swing forward, but this is resisted by the rear retarding cable 56 which is paid out by the reel 46 under the control of the gearing by which said reel is connected with the winding reel 41 and the motor. That is to say, the reel 46, which tends to rotate under the action of the tension in the cable 56, is permitted to rotate only at a rate proportioned to the rate of rotation of the front winding drum 41. Preferably the gearing connections which thus controls the rotation of the check drum 46 are such taking account of the relative diameters of the two drums 41 and 46, that the cable 56 is paid out at the same rate that the cable 44 is drawn in. Thus, it will be seen the propelling and guiding mechanism is adapted to maintain the machine at a given angle to the face as the undercut proceeds. At the same time, it is possible to readily change the angle of the machine to the face of the coal whenever this is desirable to meet the varying conditions of the material being cut, the floor of the mine, etc. Thus, if it is desired to angle the outer end of the machine rearward, the ratchet lever 51 can be applied to the check drum 46 to rotate it more or less in the direction opposite to that in which it turns in paying out the cable, thus drawing the outer end of the machine rearward. Such a movement of the outer end of the machine can, of course, be effected with the least effort if the motor is stopped, or the driving clutch 36 opened, so as to ease the tension in the propelling cable. On the other hand, if it is desired to angle the outer end of the machine forward relative to the inner end, this can be done by disengaging the pawl 48 and permitting the reel 46 to turn relative to the sleeve 49 so as to pay out the cable 56 more rapidly than the gearing which controls the rotation of the drum 46 would normally permit.

I have referred above to the propelling and guiding mechanism as adapted to maintain the machine at a given angle to the face. Under some conditions, however, as for example, when impurities of great density and hardness are encountered by the cutters, it is desirable that the machine have greater flexibility in its movements. When the cutters meet abnormally great resistance, there is danger of breakage of some part or parts of the machine if the mechanism is such that an unvarying movement of the machine is necessary regardless of the resistance encountered. In the case of my improved machine the propelling reel 41 is driven from the motor through the friction clutch 41^a which can be set to slip when the tension in the draft cable 44 reaches any amount determined upon. Therefore, when the cutters encounter an abnormally high resistance due to hard impurities or the like,

such increased resistance, if sufficiently great, will result in slippage between the parts of the friction clutch 41^a so that the winding reel 41 is driven at a slower speed. Thus, the advance of the machine is retarded and the cutters are given an opportunity to cut through the harder material. It will be observed that when the drum 41 is driven at slower speed by reason of the slippage of the clutch, the outer retarding drum 46 will continue to rotate and pay out the retarding cable 56 at the same rate as before. Thus, while the slippage is occurring, the outer end of the machine is permitted to gradually swing forward relative to the inner end. When this swinging of the machine has continued for a little time, it can be stopped and the outer end swung rearward again by means of the ratchet lever 51 in the manner previously described. This swinging forward and backward of the machine is often of great advantage in cutting through hard foreign materials which are, in many cases, in the form of nodules or boulder like bodies. For example, if a sulfur ball, lying in some distance from the face, is encountered by the cutters, the movements of the machine will be as above described; that is, the increased resistance to the cutters, assuming that it is sufficiently great, will result in the slippage of the clutch which drives the reel 41 permitting the cutter bar to advance more slowly while the outer end of the machine advances more rapidly. As the outer end of the machine swings forward, the angle of attack of the cutters is constantly changed and then, when the outer end of the machine is swung rearward in the manner described, there is a further material change in the angle of attack of the cutters, and this facilitates the cutting because it tends to loosen the sulfur ball or nodule and break it out without cutting entirely through it. In all of these advancing and swinging movements of the machine it is free to slide in any direction over the floor of the mine, and in usual practice this free movement of the machine is facilitated by the use of flat skids. These skids, which are in the form of thin metal plates a few inches wide, are laid upon the floor of the mine in the direction of the machine's advance and, by affording a hard smooth surface for the main frame, greatly facilitate the movement of the machine.

It will be understood that the friction clutch 41^a can be set to give way under any stress within a reasonable range so that the machine can be made to cut through minor impurities or hard streaks without slippage occurring. In some deposits of coal, impurities are encountered which are of such great density and hardness or so extensive that it is impossible to attempt to cut through them. In some such cases it is possible to

carry the undercut over or under the obstruction, and my improved machine is well adapted to work under such conditions. Thus, if a roll is encountered it may be 5 found possible to back the machine off along the face to a suitable distance from the obstruction and then by blocking up the skids, which, as previously noted are commonly used with such machines, the cutters may be 10 guided in an upwardly inclined path over the obstruction and then gradually downward again to the normal level. Such a handling of the machine as this is greatly facilitated in the case of applicant's machine 15 by the fact that the winding drum and guide sheave with which the feed or propelling cable engages, and also the outer drum 46 with which the check cable 56 engages, are all mounted to turn upon horizontal axes so 20 that the cables do not interfere with the free tipping of the machine about its longitudinal axis.

Reference has already been made to the 25 box-like construction of the main frame of the machine. This I regard as a feature of much practical importance. During the cutting operation the fine coal or slack which is formed is dragged out of the kerf by the cutters and must be handled or disposed of 30 in such a way as not to clog or interfere with the cutters or other working parts of the machine. In my improved construction this fine coal is drawn into and outward through the box-like main frame to the outer end of 35 the machine by the cutters. There as the cutter chain rounds the driving sprocket wheel, the fine material falls either quite clear of the machine as it advances, or, if it is not delivered entirely clear of the machine, it is possible for the machine runner or his helper to readily shovel it away because the cutting away of the side plates of the frame at the outer end thereof leaves a 40 free space adjacent the driving sprocket wheel and beneath the upper platform part of the frame which permits ready and effective use of the shovel for the purpose stated. Furthermore, it will be observed that with the exception of the cutters and the sprocket 45 wheel which drives them, all of the working parts—gears, winding drums, clutches, motor, etc.—are mounted above the upper platform part of the frame so as to be fully protected from contamination with the fine 50 coal or slack which cannot rise and enter any of these working parts during its passage from the face outward to the point where it is delivered by the cutters free of the machine. In this connection it will be 55 observed that practically all of the gears, shafts and clutches constituting the driving mechanism are grouped compactly together on one part of the frame platform while the motor occupies another part. This arrangement of the motor and the driving gearing 60

greatly facilitates the complete protection of the gearing from dust because it makes it possible to inclose the gearing by means of a simple protecting casing.

In the foregoing description of the operation of the machine its use in room and pillar mining was considered. It will be obvious without further detailed description that the operation in making an undercut along the face would be essentially the 75 same in longwall mining. Ordinarily in longwall mining it is not necessary to make an entering or stumping cut because the cut can be started at a free face.

Referring to Figs. 1, 2 and 5, I have 80 shown means by which power may be transmitted to gearing on a suitable mining machine truck upon which the mining machine may be mounted, said gearing being for the purpose of propelling the truck. This mechanism comprises a transversely arranged shaft 68 in axial alignment with the transverse shaft 29, the inside end of which latter shaft is fitted into a recess 68' in the inside end of the shaft 68. 69 is a positive 90 clutch one element of which 69' is secured to the shaft 29 and the other element 69" is carried by the inside end of the shaft 68. The shaft 68 is suitably supported on a bearing 70 secured to the main frame. 71 95 is a sprocket wheel rigidly secured to the outside end of the shaft 68 and adapted to be connected with the propelling mechanism on the mining machine truck. When not required in use the shaft 68 may be removed 100 from the machine by drawing it longitudinally out from the bearing 70.

When the machine is to be moved from place to place in the mine, the propelling and retarding cables 44 and 56 are wound up on their respective reels 41 and 46 so that the machine is reduced to a compact form which can be conveniently handled and moved about. In the case of prior machines in which loose ended chains or cables 110 are employed, great inconvenience has been experienced in handling the machines when they were to be moved about in the mine, but in the case of my machine this inconvenience is obviated.

In the foregoing description I have indicated that the angling of the machine in relation to the coal face is effected by increasing or decreasing the length of the rear cable section by the use of the manual devices; but it is to be observed that the angling of the machine is always characterized by a change in relation to the machine of the lines along which the drafts of the cable sections are exerted on the machine. However, while I consider myself the first to produce a machine of the class in question having any kind of propelling and guiding cable system presenting a section of cable arranged to exert a forward draft on the 125 130

inner part of the main frame of the machine and a section of cable arranged to exert a rearward draft on the outer part of the main frame, together with means, 5 mounted on the machine, for varying in relation to the machine the lines along which the drafts of said sections of cable are exerted thereon, I do not in the present application make broad or generic claims to this 10 feature inasmuch as such claims are included in my co-pending application, Serial No. 684,224, originally filed September 20, 1906.

The construction of the devices for effecting the sumping cut, as shown and described, is such as is set forth and claimed in the application filed by me September 20, 1906, Serial No. 385,453; and I do not herein present claims for any of the said 20 matters of construction, the claims herein relating to the construction and arrangement of the parts by which the machine is propelled and guided or adjusted in its positions relative to the coal and relative 25 to its line of travel.

What I claim as my invention is:

1. The combination of a main frame, cutting apparatus carried thereby, a winding reel on the main frame, a cable on said reel for propelling the machine when it is in operation and adapted to be fastened to a stationary holder in advance thereof, and a guide mechanism having a cable section adapted to exert on the outer end of 30 the machine a tension backward, a reel on the main frame for winding and unwinding the last said cable, power devices for the last said reel connected to the power devices for the first aforesaid reel and 35 adapted to permit rotation of one of the said reels independently of the other, and a single motor on the main frame for driving the cutting apparatus and both of the said reels, substantially as set forth.

2. The combination of a main frame, cutting apparatus carried thereby, a winding reel on the main frame at the inner end thereof, power transmitting devices for rotating the said reel, a cable on the reel for 40 propelling the machine and adapted to be fastened to a stationary holder in advance thereof, a second cable extending from a stationary holder at the rear of the machine, a reel on the outer end of the main frame 45 for the said second cable, a driver for the second reel adapted to be connected to and disconnected from the power transmitting devices of the first aforesaid reel, and a motor on the main frame adapted to actuate 50 both the cutting apparatus and the two winding reels, substantially as set forth.

3. The combination of a main frame, cutting apparatus carried thereby, a winding reel on the main frame, gearing for driving 55 the said reel, a motor behind the said

reel and gearing and connected to drive the same, a supplemental cable secured at one end to a stationary holder in rear of the machine, a winding reel for the supplemental cable in rear of the motor, and power 70 transmitting devices connecting the last said reel with the gearing of the first aforesaid reel, substantially as set forth.

4. The combination of a main frame, cutting apparatus carried thereby, a winding 75 reel on the main frame, a cable secured to said reel and adapted to be fastened to a stationary holder in advance thereof, two trains of differently speeded power transmitting devices for the said reel, a supplemental 80 cable adapted to be secured to a stationary holder in the rear of the machine, a second winding reel on the main frame for said cable, and means for driving the said second reel with either of several speeds respectively corresponding to the speeds of the first aforesaid reel, substantially as set forth.

5. The combination of a main frame, cutting apparatus carried thereby, a winding 85 reel on the main frame, a cable on said reel for propelling the machine when it is in operation and adapted to be fastened to a stationary holder in advance thereof, and a guide mechanism having a cable section 90 adapted to exert on the outer end of the machine a tension backward, a reel on the main frame for winding and unwinding the last said cable, a motor on the main frame, and driving connections between the motor and 95 said reels for turning the latter in definite relation to each other or in optionally variable relations, substantially as set forth.

6. The combination of a main frame, cutting apparatus carried thereby, a winding 100 reel mounted on the main frame, a cable secured to said reel and adapted to be fastened to a stationary holder in advance of the machine, means comprising a speed changing 105 transmission mechanism for driving said winding reel, a supplemental cable adapted to be secured to a stationary holder in the rear of the machine, a second winding reel on the main frame to which said cable is secured, and means for driving said second 110 reel in unison with the first reel at whatsoever speed the latter is driven, substantially as set forth.

7. The combination of a main frame, cutting apparatus carried thereby, a winding 115 reel on the main frame, a cable secured to said reel and adapted to be fastened to a stationary holder in advance of the machine to propel it, a second winding reel mounted on the main frame, a retarding cable secured to 120 said reel and adapted to be fastened to a stationary holder in the rear of the machine, means adapted normally to cause the rotation of the retarding cable reel in unison 125 with the propelling cable reel whereby the 130

- retarding cable is normally paid out at the same rate as the propelling cable is drawn in, and means permitting a rotation of the retarding cable reel relative to the propelling cable reel to vary the angle of the machine to the face of the coal.
8. The combination of a main frame, cutting apparatus carried thereby, a winding reel on the main frame, a propelling cable
- 10 having one end secured to said reel and its other end adapted to be secured to a stationary holder in advance of the machine so as to exert a forward draft on the inner end of the main frame, a second reel mounted on
- 15 the main frame, a retarding cable having one end secured to said reel and its other end adapted to be secured to a stationary holder in the rear of the machine so as to exert a rearward draft on the outer end of the machine, power devices for driving the aforesaid reels, and means on the machine frame for variably controlling the rotation of the second named reel to pay out the retarding cable as the machine advances.
- 20 9. The combination of a main frame, cutting apparatus carried thereby, a winding reel on the main frame, a propelling cable secured to said reel and adapted to be fastened to a stationary holder in advance of
- 25 the machine, a second reel on the main frame, a retarding cable secured to said reel and adapted to be fastened to a stationary holder in the rear of the machine, a motor on the main frame, and driving connections between said motor and the two reels to cause their simultaneous rotation for winding up the propelling cable and paying out the retarding cable, the driving connections for one of said reels being yieldable.

10. The combination of a main frame, cutting apparatus carried thereby, a winding reel on the main frame, a propelling cable secured to said reel and adapted to be fastened to a stationary holder in advance of the machine, power devices comprising a yieldable driving connection for rotating the said reel, a second reel on the main frame, a retarding cable secured to the last named reel and adapted to be secured to a stationary holder in the rear of the machine, means for causing the second reel to rotate simultaneously with the first named reel so that the retarding cable is paid out as the propelling cable is wound up, the second reel being rotatable at will independently of the first named reel whereby the outer end of the machine, when desired, can be swung rearward.

11. In a mining machine the combination with cutting means of flexible guiding means comprising a pair of flexible guiding members connected each to a fixed support, one on the advancing side of the machine and the other on the receding side thereof and connected to the machine, one near the wall or cutting end and the other nearer the opposite end thereof, a winding drum for said first named guiding member, a winding drum for said second named guiding member, drum clutching and unclutching means, and means for manually turning one drum independently of the other.

In testimony whereof I affix my signature, in presence of two witnesses.

WALTER F. TROTTER.
